EXTRACTOR-AND-EJECTOR ASSEMBLY
FOR FIREARMSArthur A. Rowley, Hamden, Conn., assignor to
Western Cartridge Company, New Haven,
Conn., a corporation of Delaware

Application April 13, 1943, Serial No. 482,837

5 Claims. (Cl. 42—25)

The present invention relates to improvements in firearms and relates more particularly to improvements in extractor-and-ejector assemblies which include a movable breech-bolt.

One of the objects of the present invention is to provide a superior extractor, ejector and breech-bolt assembly wherein the said ejector will serve to prevent the unintentional detachment of the said extractor from the said breech-bolt.

A further object of the present invention is to provide a superior construction and arrangement of parts whereby a cartridge-extractor and a cartridge-ejector will each serve to retain the other in place in a movable breech-bolt or its equivalent.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a top or plan view of a breech-bolt in which is incorporated a cartridge-extractor and cartridge-ejector assembly in accordance with the present invention;

Fig. 2 is a side view thereof;

Fig. 3 is an underside view thereof;

Fig. 4 is a view thereof in front end elevation;

Fig. 5 is a broken longitudinal sectional view of the forward end of the breech-bolt taken on the line 5—5 of Fig. 4, and in addition showing the cartridge-extractor in the foreground and the cartridge-ejector held in its retired position by a cartridge-casing;

Fig. 6 is a broken detail sectional view taken on the line 6—6 of Fig. 4;

Fig. 7 is a broken transverse sectional view taken on the line 7—7 of Fig. 6;

Fig. 8 is a view corresponding to Fig. 6 but showing the cartridge-ejector retired by the engagement of the head-end of a cartridge-casing with the forward end of the said cartridge-ejector;

Fig. 9 is a broken transverse sectional view taken on the line 9—9 of Fig. 8;

Fig. 10 is a perspective view of the cartridge-extractor, detached; and

Fig. 11 is a similar view of the cartridge-ejector.

For purposes of illustrating one embodiment of the present invention, there is shown in the accompanying drawings, a breech-bolt generally

designated by the reference character 15 which is, generally speaking, of cylindrical form save for a lightening-cut 16 in its upper face and two radially-projecting locking-lugs 17 and 18 integrally formed at its forward end. The two said locking-lugs 17 and 18 extend radially outwardly from the breech-bolt 15 at substantially-diametrically-opposite points thereon and are adapted to move into and out of suitable locking-recesses in a firearm in a manner well known in the art and illustrated, for instance, in the well-known Garand military rifle.

In its forward face, the breech-bolt is formed with a recess 19 which is adapted to successively receive the head-ends of cartridge-casings such, for instance, as the cartridge-casing 20 illustrated in Figs. 5 and 8. Extending axially through the breech-bolt 15 is a passage 21 in which is adapted to reciprocate a suitable firing-pin (not shown) in a manner well understood in the art.

Eccentrically of and parallel with the axial passage 21 in the breech-bolt 15, the said breech-bolt is formed with a forwardly-opening pocket or ejector-receiving passage 22 in which reciprocates a rod-like cartridge-ejector 23. The forward end of the cartridge-ejector 23 is positioned so as to extend forwardly into the recess 19 in the front face of the breech-bolt 15, for purposes of engaging with a cartridge-casing such as 20 and ejecting the same, all in a manner as will more fully hereinafter appear. The said cartridge-ejector 23 is yieldingly urged forwardly by a helical ejector-spring 24 interposed between the rear end of the cartridge-ejector and the bottom of the cylindrically-contoured pocket 22 in which the said cartridge-ejector reciprocates.

On its inner face the otherwise cylindrically-contoured cartridge-ejector 23 is formed with a clearance-notch 25, the sloping rear wall of which constitutes a stop-abutment 26 acting in a manner as will hereinafter appear to limit the forward movement of the cartridge-ejector 23 under the urge of the ejector-spring 24. The under face of the portion of the cartridge-ejector 23 lying immediately forwardly of the forward end of its notch 25 acts on occasion as a stop-abutment 27 to limit the movement of a cartridge-extractor, in a manner as will hereinafter appear.

Laterally intersecting both the axial passage 21 and the ejector-receiving passage 22 in the breech-bolt 15 and extending substantially perpendicularly with respect thereto, is a cylindrically-contoured vertical passage 28 which re-

ceives the vertical cylindrically-contoured stem 29 of a cartridge-extractor generally designated by the reference character 30. In addition to its stem 29, the cartridge-extractor 30 includes a body-portion 31 having at its forward end a hook-like cartridge-extracting lip 32 adapted to fit into a cannelure 33 formed in the cartridge-casing 20 immediately forwardly of its rear face.

The body-portion 31 of the cartridge-extractor 30 is accommodated in a recess 34 in the upper portion of the breech-bolt 15 and extends part way into the locking-lug 18 thereof. The vertical cylindrically-contoured passage 28 for the accommodation of the stem 29 leads downwardly from the bottom of the said recess 34 and through the under face of the breech-bolt 15.

For the purpose of yieldingly urging the cartridge-extractor 30 to turn in a direction to urge its cartridge-extracting lip 32 into the cannelure of a cartridge-casing, an extractor-plunger 35 is employed. The said extractor-plunger reciprocates in the forward end of a pocket 36 formed in the outwardly-and-forwardly-sloping rear wall of the recess 34 in the breech-bolt 15. Interposed between the inner end of the extractor-plunger 35 and the bottom of the pocket 36 is a helical extractor-spring 37 urging the said extractor-plunger into engagement with a shallow conical recess 38 in the adjacent face of the body-portion 31 of the cartridge-extractor 30.

In its inner face adjacent its lower end, the stem 29 of the cartridge-extractor 30 is formed with a clearance-notch 39 facing slightly forwardly but mainly toward the cartridge-ejector 23. The curved lower wall of the said clearance-notch 39 constitutes a stop-abutment 40 adapted to engage with the stop-abutment 27 of the cartridge-ejector 23, in a manner as will hereinafter appear. The portion of the stem 29 which is located immediately to the rear of the clearance-notch 39 constitutes a rearwardly-facing stop-abutment 41 which is adapted to be engaged by the forwardly-facing stop-abutment 26 of the cartridge-ejector 23.

In assembling the parts above described, the extractor-spring 37 and the extractor-plunger 35 may be installed in the pocket 36 in the breech-bolt, and the cartridge-extractor 23 and the ejector-spring 24 may be installed in the longitudinal pocket 22. Now by manually forcing the cartridge-extractor 23 into a position very slightly rearwardly of the position in which it is shown in Fig. 6, the clearance-notch 25 therein will be brought into full unobstructing registry with the vertical passage 28. Under these conditions, the cartridge-extractor 30 may be installed in the breech-bolt by a downward movement causing its stem 29 to pass downwardly through the vertical passage 28 and through the now-registering clearance-notch 25 in the cartridge-extractor 23 until the said cartridge-extractor is fully in place. In moving downwardly, the body-portion 31 of the cartridge-extractor will cam the extractor-plunger 35 rearwardly and outwardly until the conical recess 38 in the cartridge-extractor is brought into registry with the said extractor-plunger, whereupon the said extractor-plunger will snap into the said recess 38. The full registry of the recess 38 and the extractor-plunger 35 will occur when the cartridge-extractor has been fully seated in the breech-bolt and when the clearance-notch 39 in the stem 29 is in horizontal registry with the cartridge-ejector 23.

As soon as the cartridge-ejector 23 is released from rearward manual restraint, the ejector-

spring 24 will assert itself and will move the cartridge-ejector slightly forwardly to engage the forwardly-facing stop-abutment 26 thereof with the rearwardly-facing stop-abutment 41 of the stem 29 to limit the forward movement of the cartridge-ejector, all as shown particularly well in Fig. 6 of the drawings.

Under the conditions above described, the stem 29 of the cartridge-extractor 30 will act as stop means to limit the forward movement of the cartridge-ejector 23, but the said cartridge-ejector will not under these conditions act as a stop to limit the axial movement of the stem 29.

When in the operation of the firearm the head-end of a cartridge-casing such as 20 is seated in the recess 19 in the forward end of the breech-bolt and is engaged by the cartridge-extracting lip 32, the cartridge-ejector will be held in its rear position as shown in Figs. 5, 8 and 9. In this position, the stop-abutment 27 adjacent the forward end of the clearance-notch 25 in the cartridge-ejector 23 will be entered into the clearance-notch 39 in the stem 29 of the cartridge-extractor 30. Under these conditions, should centrifugal or other forces tend to throw the cartridge-extractor 30 outwardly from the recess 34 in the breech-bolt 15, the engagement of the stop-abutment 40 with the stop-abutment 27 will positively prevent such displacement.

In self-loading firearms in particular, the discharge of a cartridge effects a very rapid turning movement of the breech-bolt 15 followed by a rearward travel thereof in a manner well understood in the art. It is during this very sharp or rapid turning movement that centrifugal force tends to displace the cartridge-extractor 30. Now inasmuch as this rapid, sharp turning and rearward travel of the breech-bolt can take place only when a cartridge-casing is seated in the recess 19 in the forward end of the breech-bolt, the very fact of the presence of such cartridge-casing serves to automatically hold the cartridge-ejector 23 in position whereby its stop-abutment 27 is interposed in the path of the stop-abutment 40 of the stem 29 to thereby positively prevent the outward displacement of the cartridge-extractor. In addition, the stem 29 of the cartridge-extractor 30 serves as means to limit the forward movement of the cartridge-ejector 23 in the manner previously described.

By means of the present invention, a cartridge-ejector and a cartridge-extractor may each serve to limit the movement of the other.

The terms "vertical," "upwardly," "downwardly," or their equivalents, as used herein are applicable when the breech-bolt 15 is turned into a position wherein the stem 29 of the cartridge-extractor 30 extends vertically and the body-portion 31 thereof is uppermost.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An extractor-and-ejector assembly for firearms, including in combination: a breech-bolt having an ejector-receiving passage extending longitudinally in and intersecting the forward end thereof, the said breech-bolt also having an extractor-receiving passage extending vertically

transversely of the said breech-bolt and laterally intersecting the said ejector-receiving passage therein; a cartridge-ejector reciprocating in the ejector-receiving passage in the said breech-bolt and provided with a downwardly-facing stop-abutment movable transversely into the extractor-receiving passage in the said breech-bolt when the said cartridge-ejector is retired rearwardly relative to the said breech-bolt; spring-means urging the said cartridge-ejector forwardly with respect to the said receiver; and a cartridge-extractor having a stem extending into and turning in the extractor-receiving passage in the said breech-bolt and formed with an upwardly-facing stop-abutment normally located below the path of movement of the said cartridge-ejector and engageable with the downwardly-facing stop-abutment of the said cartridge-ejector when the latter is moved into its retired position by the engagement of a cartridge-casing therewith, to thereby positively hold the said cartridge-extractor against withdrawal from the said breech-bolt.

2. An extractor-and-ejector assembly for firearms, including in combination: a breech-bolt having an ejector-receiving passage extending longitudinally in and intersecting the forward end thereof, the said breech-bolt also having an extractor-receiving passage extending transversely of the breech-bolt and laterally intersecting the said ejector-receiving passage therein; a cartridge-ejector reciprocating in the ejector-receiving passage in the said breech-bolt and formed on its side with a clearance-notch facing toward the extractor-receiving passage in the said breech-bolt; spring-means urging the said cartridge-ejector forwardly with respect to the said receiver; and a cartridge-extractor having a stem extending into and turning in the extractor-receiving passage in the said breech-bolt and formed with a laterally-opening clearance-notch facing toward the said cartridge-ejector; the clearance-notch in the said cartridge-ejector and the clearance-notch in the said cartridge-extractor being positioned with respect to each other so that when the said cartridge-ejector is in a forward position the clearance-notch therein registers with the stem of the said cartridge-extractor to permit the withdrawal thereof, and when the said cartridge-ejector is retired rearwardly by a cartridge-casing, a portion of the said cartridge-ejector is positioned in the clearance-notch in the stem of the said cartridge-extractor to thereby positively hold the same against withdrawal from the breech-bolt.

3. An extractor-and-ejector assembly for firearms, including in combination: a breech-bolt having an ejector-receiving passage extending longitudinally in and intersecting the forward end thereof, the said breech-bolt also having an extractor-receiving passage extending transversely of the breech-bolt and laterally intersecting the said ejector-receiving passage therein; a cartridge-ejector reciprocating in the ejector-receiving passage in the said breech-bolt and formed on its side with a clearance-notch facing toward the extractor-receiving passage in the said breech-bolt; spring-means urging the said cartridge-ejector forwardly with respect to the said receiver; and a cartridge-extractor having a stem extending into and turning in the extractor-receiving passage in the said breech-bolt and formed with a lateral clearance-notch facing forwardly and toward the said cartridge-ejector; the two said clearance-notches being positioned

with respect to each other so that when the said cartridge-ejector is in a forward position, the clearance-notch therein is in registry with the stem of the said cartridge-extractor to permit the withdrawal thereof, and when the said cartridge-ejector is retired rearwardly by a cartridge-casing, a portion of the said cartridge-ejector is positioned in the clearance-notch in the stem of the said cartridge-extractor to thereby positively hold the same against withdrawal from the breech-bolt.

4. An extractor-and-ejector assembly for firearms, including in combination: a breech-bolt having an ejector-receiving passage extending longitudinally in and intersecting the forward end thereof, the said breech-bolt also having an extractor-receiving passage extending transversely of the said breech-bolt and laterally intersecting the said ejector-receiving passage therein; a cartridge-ejector reciprocating in the ejector-receiving passage in the said breech-bolt and formed on its side with a clearance-notch facing toward the extractor-receiving passage in the said breech-bolt; spring-means urging the said cartridge-ejector forwardly with respect to the said receiver; and a cartridge-extractor having a stem extending into and turning in the extractor-receiving passage in the said breech-bolt and formed with a laterally-opening clearance-notch facing toward the said cartridge-ejector; the clearance-notch in the said cartridge-ejector and the clearance-notch in the said cartridge-extractor being positioned with respect to each other so that when the said cartridge-ejector is at the limit of its forward movement, the rear wall of the clearance-notch therein engages with the stem of the said cartridge-extractor to limit the forward movement of the said cartridge-ejector; the two said clearance-notches also being positioned and related with respect to each other so that when the said cartridge-ejector is retired rearwardly by a cartridge-casing, the portion of the said cartridge-ejector adjacent the forward end of the clearance-notch therein is positioned in the clearance-notch in the stem of the said cartridge-extractor to thereby positively hold the same against withdrawal from the said breech-bolt; the clearance-notch in the said cartridge-ejector having an extent in a direction lengthwise of the cartridge-ejector sufficient to fully clear the stem of the said cartridge-extractor when the cartridge-ejector is positioned intermediate its full forward position and its retired position.
5. An extractor-and-ejector assembly for firearms, including in combination: a breech-bolt having an ejector-receiving passage extending longitudinally in and intersecting the forward end thereof, the said breech-bolt also having an extractor-receiving passage extending transversely of the said breech-bolt and laterally intersecting the said ejector-receiving passage therein; a cartridge-ejector reciprocating in the ejector-receiving passage in the said breech-bolt and formed on its side with a clearance-notch facing toward the extractor-receiving passage in the said breech-bolt; spring-means urging the said cartridge-ejector forwardly with respect to the said receiver; and a cartridge-extractor having a stem extending into and turning in the extractor-receiving passage in the said breech-bolt and formed with a lateral clearance-notch facing forwardly of the breech-bolt and inwardly toward the said cartridge-ejector; the two said clearance-notches being positioned with respect

to each other so that when the said cartridge-ejector is retired rearwardly by a cartridge-casing, the portion of the said cartridge-ejector adjacent the forward end of the clearance-notch therein is positioned in the forwardly- and inwardly-facing clearance-notch in the stem of the said cartridge-extractor to thereby positively hold the same against withdrawal from the said breech-bolt; the two said clearance-notches also being positioned and related with respect to each other so that when the said cartridge-ejector is at the normal limit of its forward movement, the

rear wall of the clearance-notch therein engages with the stem of the said cartridge-extractor to limit the forward movement of the said cartridge-ejector; the clearance-notch in the said cartridge-ejector having an extent in a direction lengthwise of the cartridge-ejector sufficient to fully clear the stem of the said cartridge-extractor when the cartridge-ejector is positioned intermediate its full forward position and its re-tired position.

10

ARTHUR A. ROWLEY.
